CAR CONSTRUCTION

Otho C. Duryea, Waterbury, Conn., assignor to
O. C. Duryea Corporation, Wilmington, Del.,
a corporation of Delaware

**Application October 2, 1936, Serial No. 103,787
Renewed January 22, 1938**

23 Claims. (Cl. 213—8)

This invention relates to railway car constructions having underframes of the Duryea type which provide long travel for resisting draft and buffering shocks with low forces together with short travel for train slack which is predetermined independently of and is less than said long travel. In one form which is well known in the art, the Duryea underframe comprises a long travel draft and buffering column which extends longitudinally and slidably with respect to the car body bolsters and couplers mounted at the ends of said column for limited movement relative thereto to provide train slack, long travel cushioning means being interposed between said column and the car body bolsters for resisting and absorbing draft and buffering forces.

The present invention relates more particularly to long travel cushioning means of the above type which comprise both friction and resilient means 20: for absorbing draft and buffing forces, and one of its objects is to provide such long travel cushioning means which is constructed in a novel manner so as to produce a strong and rugged yet simple and inexpensive cushioning gear.

25 Another object of the invention is to provide a novel long travel cushion gear of the type embodying both friction and resilient means which is disposed entirely or substantially entirely between the car body bolster and the adjacent end 30 of the car.

Another object is to provide a novel long travel cushioning gear embodying both friction and resilient means and adapted to cushion the car body against draft and buffing shocks and also to cushion the train slack movement of the coupler.

A further object is to provide a combined bolster and cushion gear comprising a novel long travel cushion gear embodying resilient and friction means and housed in a casing or housing formed as a part of the bolster construction.

Another object is to provide a novel integral construction comprising both a bolster and a housing.

45 Other objects will appear more fully herein-
after as the description proceeds.
One embodiment of the invention has been
illustrated in the accompanying drawings but it
is to be expressly understood that said drawings
50 are for purposes of illustration only and are not
to be construed as a definition of the limits of
the invention, reference being had to the ap-
pended claims for this purpose.

In the drawings,

55. Figs. 1 and 1a together constitute a plan view, partly in section, of one end of a car underframe embodying the invention;

Figs. 2 and 2a together constitute a vertical section on the central line of the construction shown in Figs. 1 and 1a;

Fig. 3 is a section on the line 3—3 of Fig. 2;
 Fig. 4 is a section on the line 4—4 of Fig. 2a; and
 Fig. 5 is a section on the line 5—5 of Fig. 2a.

Referring to the drawings, wherein like reference numerals indicate like parts, the car body (not shown) is provided with suitable body bolsters whereby the car is supported on the usual trucks and which usually embody center brace castings one of which is shown in Figs. 1 and 2 at 10. Extending longitudinally and slidably with respect to said center brace casting 10 is a draft and buffering column which may be of any suitable type and construction and which in the form shown comprises two spaced channels 11, 11 that embrace the casting 10 and are connected together at suitable points by means of top and bottom cover plates 12 and 13, respectively. Adjacent the casting 10, where cover plates cannot be employed, said column may be strengthened by the provision of plates 14 (Fig. 1) secured in any suitable manner as by welding between the edges of the flanges of said channels 11, 11.

A suitable coupler 15 (Figs. 1a and 2a) is mounted at the end of said column, preferably for limited movement relative thereto to provide train slack. The extent of such train slack movement can be predetermined and made as small as desired, and in the form shown said coupler is mounted so as to be movable inwardly with respect to said column through a short distance, say about one inch or less, which provides train slack on buff, but so as to be incapable of outward movement with respect to said column so that no train slack is provided on draft. A suitable construction of this type is shown in Figs. 1a and 2a, wherein a coupler of the swivel butt type is shown. As shown in these figures, the shank of the coupler 15 extends inwardly between the channels 11, 11 and is provided with a slot 40 through which extends a key 16 retained in position by a head 17 and a pin 18. The longitudinal dimension of said slot is greater than the dimension of said key so as to provide a space 19 as shown in Fig. 1. Laterally of the coupler shank, said key extends through openings in the webs of the channels 11, 11, and to provide greater strength, cheek plates 20 are preferably secured to said channels in any suitable manner as by welding, said cheek plates being provided with strengthening flanges 21 which surround and define slots therethrough in alignment with the openings in said channel webs. The longitudinal dimensions of these slots are greater than the dimensions of the key 16 so as to provide spaces 50 22 shown in Fig. 1. The butt of the coupler terminates in spaced parallel webs 23 which are interleaved with similar spaced parallel webs 24 of a swivel casting 25, the contacting ends of webs 23 and 24 being curved about the center 55 60 65 70 75 80 85 90 95 100

of a vertical pin 25'. On draft, the draft force is transmitted from the coupler butt through the pin 25', the swivel casting 25, key 16 and flanges 21 to the column 11, 11. On buff, the buffing force moves the coupler and swivel casting 25 inwardly relative to said column through a distance limited as hereinafter described and less than the sum of spaces 19 and 22, which relative movement provides train slack on buff only.

10 Means are provided whereby the inward movement of the coupler 15 relative to the draft and buffing column, as well as further inward movement of said coupler and column and outward movement of said coupler and column, is resisted both resiliently and frictionally. To this end friction wedge means are provided that move relative to said column on inward movement of the coupler 15 relative thereto and together with said column on further inward movement and on outward movement of said coupler, together with resilient means that are compressed on inward and outward movement of said coupler or column. Thus train slack movement of the coupler and long travel cushioning movement are resisted by compression of said resilient means, which may also be utilized to maintain frictional engagement between suitable friction elements and said wedge means whereby draft and buffing forces are resisted both frictionally and resiliently.

15 20 25 30 35 40 45 50 55 60 65 70 75

In the form shown, said wedge means comprise longitudinally extending plates having friction surfaces on their outer sides whereby they engage frictionally with the column 11, 11 and inclined wedge surfaces on their inner sides which are in frictional engagement with suitable friction shoes. The arrangement of said wedge surfaces may be such as to provide for equal frictional effect in both directions of movement of the coupler from a normal position, or otherwise, and the wedge surfaces may be so inclined as to provide greater resistance to movement of said column away from normal position than toward normal position, or vice versa. In the form shown, the wedge means comprise plates 26 having plane outer friction surfaces in engagement with the inner faces of the webs of the channels 11, 11 and inner inclined wedge surfaces which increase in height in opposite directions from their central portions. As shown in Fig. 1a, the outer friction surfaces of said wedges 26 are preferably provided with vertical slots or grooves 27 whereby any chips formed during the frictional action of the cushioning gear can escape from between the wedges and the channels. For causing inward movement of said wedges 26 as a unit with the coupler 15, said wedges are shown as integrally connected by a head 28 having a central projection 29 that engages in a similar recess in the swivel casting 25. Said wedges 26 are accordingly moved relatively to the column 11, 11 on inward movement of said coupler relative to said column for train slack purposes. Beyond said limited coupler movement, however, means are provided whereby both the wedges 26 and the column 11, 11 are moved inwardly as a unit by the coupler, this end being accomplished in the form shown by providing the head 28 with upper and lower flanges 30 adapted to engage upper and lower stop plates 31 secured to the channels 11. The total train slack movement of the coupler is thus determined by the spacing between flanges 30 and plates 31.

Inward movement of the coupler 15, wedges 26 and column 11, 11 is further resisted frictionally by engagement between the inner wedge sur-

faces thereof and suitable friction shoes that are held against longitudinal movement in any suitable manner. In the form shown, each wedge 26 is engaged by two friction shoes 32 one on each side of the central portion of said wedge, said 5 shoes as shown in Fig. 1a being substantially triangular in cross section and being held against longitudinal movement by vertical walls 33 forming a substantially diamond-shaped friction member that is secured to the car body in any 10 suitable manner. For maintaining the friction member against longitudinal movement it is preferably connected with the car body bolster, and in the construction shown in the drawings, this is accomplished by forming said friction member 15 as an integral part of the center brace casting 10, the longitudinally extending connections between said castings forming a housing for the cushioning gear. As shown in Figs. 1, 1a, 2 and 2a, the casting 10 is provided with upper and 20 lower longitudinally extending horizontal arms 36 which extend laterally close to the webs of the channels 11, said arms 36 constituting top and bottom walls which are connected by the vertical walls 33. Arms 36 and walls 33 can be secured to 25 said casting 10 and to each other in any suitable manner as by welding or may be cast integrally. Accordingly, this construction provides bolster construction 10 integral with a housing formed by the horizontal arms 36 and with the vertical 30 walls 33, whereby the friction shoes 32 and the resilient means hereinafter described are carried and housed.

Movement of the coupler 15, wedges 26 and column 11, 11 is also resisted by suitable resilient 35 means which are operatively connected with the friction shoes 32, suitable connections being provided whereby said resilient means is compressed against the inner shoes 32 or outer shoes 32 depending on whether the wedges 26 move outwardly or inwardly. Preferably, said resilient means is disposed in the housing constituted as described above and comprises a coil spring 37, the inner end of which may if desired extend through a suitable opening in the center brace 40 casting 10 as shown in Figs. 1 and 2. As shown in Figs. 1 and 2, said inner end of spring 37 rests against a follower plate 38 that is engaged by a head 39 of a link 40 extending longitudinally through the entire length of said spring 50 and through suitable openings in the vertical walls, said link 40 being provided at its other end with a key 41 engaging the outer friction shoes 32. As shown, the ends of the key are provided with wear pads 42 pivotally mounted 55 on said key in any suitable manner at 43 and engaging the outer faces of said friction shoes 32. Spring 37 thereby holds the outer friction shoes 32 normally in engagement with the friction surfaces 34 of the casting 33. When said 60 shoes are released by the spring under the action of a draft force as hereinafter described, said shoes are prevented from being displaced by suitable connections to the arms 36 which in the form shown comprise lugs 44 on the upper 65 and lower ends of the shoes, the shoes fitting between the arms 36 and said arms being notched as indicated by the dotted lines 45 in Fig. 1a to receive the lugs 44. A similar connection is preferably made between the inner friction shoes 70 32 and the arms 36.

The spring 37 is compressed against the follower plate 38 and therefore against the outer friction shoes 32 on inward movement of the coupler, wedges and column by any suitable 75

means connected to one of said elements and adapted to engage the outer end of said spring. In the form shown, said outer end is seated in a recess formed in a casting 46 the bottom plate 47 of which constitutes a spring follower through which the link 40 passes freely and the other end of which is provided with a flanged head 48 adapted to be engaged by the inner ends of the wedge means 26. By this means the follower 47 is moved inwardly together with said coupler 15 and wedge means 26 to compress the spring 37 which thereby affords resilient resistance to draft forces in addition to maintaining the frictional engagement of the outer friction shoes 32 with the wedges 26 and friction surfaces 34.

Similar means are provided for engaging the inner end of spring 37 on outward movement of the coupler, wedges and column, under draft forces to compress said spring against the inner friction shoes 32. In the form shown, suitable stops 49 are secured to the webs of the channels 11, 11 by means of rivets 50 and are disposed so as to engage the follower plate 38 on outward movement of the column. The casting 47 is normally held by the wedge means 26 in a position wherein the follower 47 is spaced from the inner friction shoes 32 as shown at 51 in Fig. 1a. Outward movement of the column 11, 11 under a draft force, therefore, first compresses said spring against the wedges 26 and after said wedges have been moved outwardly a distance equal to the space 51, said follower 47 engages the inner friction shoes 32. In the meantime stops 31 of the column 11, 11 engage the flanges 30 of the head 28 whereby said wedges 26 continue to move outwardly as a unit with the column 11, 11 but the spring 37 is then compressed against the inner friction shoes 32, maintaining frictional engagement between said shoes and the wedges 26 and friction surfaces 35 whereby draft forces are resisted both resiliently and frictionally.

In operation, when a buffing force is applied to the coupler 15, said coupler first moves inwardly relative to the column 11, 11 through a limited extent which provides train slack. This movement of the coupler is resisted frictionally by friction between the outer surfaces of the wedges 26 and the inner surfaces of the webs of the channels 11, 11 and by the outer friction shoes 32 which are wedged between the wedges 26 and the friction surfaces 34, and resiliently by compression of the spring 37 against the follower plate 38 due to the engagement of the wedges 26 with the head 48 of the follower 47. When the coupler 15 has traveled inwardly relative to the column sufficiently to engage the flanges 30 with the steps 31, the coupler, column 11, 11 and wedges thereafter move inwardly as a unit, continuing the compression of the spring and also the frictional resistance of the outer friction shoes 32. Movement of the column can continue throughout a predetermined distance which in the form shown is limited by stops 52 secured to the column 11 and adapted to engage the outer face of the center brace casting 10. This movement of the column, which absorbs buffing shocks, is preferably made long as compared with the conventional draft gear in order to protect the car body against high forces and, for example, the travel of the column may be of the order of seven to nine inches, although it will be understood that larger travel may be provided when desirable since this cushioning

travel is independent of the coupler travel which provides train slack. As soon as the buffing force has been absorbed, the spring 37 expands and returns the parts to the position shown in the drawings. The return of the column 11, 11 to normal position is snubbed frictionally by the outer friction shoes 32 which are subject to the compression of the spring 37, whereby excessive recoil is avoided.

When a draft force is applied to the coupler 15 at the end of the car shown in the drawings, the column 11, 11 is moved outwardly without slack movement of said coupler relative thereto. Stops 49 engage the follower plate 38 and compress spring 37 against the wedges 26, moving said wedges outwardly until the follower 47 engages the inner friction shoes 32. Movement of the column 11, 11 also results in the engagement of stops 31 with flanges 30 of the head 28 whereby the wedges 26 and column 11, 11 move outwardly as a unit and this movement of the column is resisted resiliently by compression of spring 37 as well as by the inner friction shoes 32 that are wedged by said spring between the wedges 26 and the friction surfaces 35. Outward movement of column 11, 11 can continue until limited by suitable means such as stops 53 secured to the channels 11, 11 and adapted to engage the inner face of the center brace casting 10, the extent of this outward movement for cushioning draft forces being preferably equal to the inward movement provided for cushioning buffing forces. When the draft force has been absorbed, spring 37 expands and restores the parts to the position shown in the drawings. This return movement of the column is snubbed by the frictional resistance of the inner friction shoes 32 whereby excessive recoil is prevented.

It will be understood that a similar cushion gear is preferably provided at the opposite end 40 of the car. Hence draft and buffing forces are resisted at both ends of the car, the action of a buffing force on the end of the car shown in the drawings being the same as that of a draft force applied to the other end of the car, 45 and vice versa. Hence in either direction of movement at either end of the car, the total resistance to movement is the sum of the resistances to draft and buffing forces as described in detail above.

In addition to the operations and functions described above, it will be observed that the construction shown and described embodies novel bolster and housing construction combined with a cushion gear. Bolster casting 10 together with arms 36 and vertical walls 33 constitute a unit which can be cast or welded into a single structural unit and constitutes a housing for the cushion gear with which it can be assembled and installed as a unit. With shoes 32 and spring 37 in place and said spring installed under initial compression, the combined bolster, housing and gear are a unit that is self-contained and ready for installation as a unit in a car for use with a draft and buffing column. From this aspect 65 of the invention, wedges 26 and other parts of the construction are not necessary and can be omitted in some cases, the friction shoes engaging directly on the column itself.

It will further be apparent that the invention provides novel cushioning means that are simple in construction and occupy small space, being substantially between the bolster and the end of the car. At the same time the cushioning gear effectively absorbs draft and buffing shocks 75

with low forces on the car body. The friction means described act not only to absorb said draft and buffing forces but also to provide a snubbing action which prevents excessive recoil 5 of the column in returning to normal position under the action of the spring.

While only one embodiment of the invention has been described and illustrated in the drawings, it will be understood that the invention 10 is capable of a variety of mechanical embodiments many of which will now be apparent to those skilled in the art, and that changes may be made in the form, details of construction and arrangement of the parts, all without deviating from the spirit of the invention. Reference is accordingly to be had to the appended 15 claims for a definition of the limits of the invention.

What is claimed is:

20 1. In a railway car, the combination of a column movable longitudinally relative to the car body under draft and buffing shocks, a coupler mounted at the end of the column for movement of limited extent relative thereto, wedge means 25 frictionally engaging said column and movable relative thereto by said coupler throughout said limited extent, both said wedge means and column being moved by said coupler when said coupler moves beyond said limited extent, friction shoes engaging said wedge means, means holding said shoes against longitudinal movement, and resilient means operatively interposed between said friction shoes and column for resisting movement of said column and for maintaining frictional engagement between said shoes 35 and wedge means.

2. In a railway car, the combination of a body bolster, a column movable longitudinally relative thereto under draft and buffing shocks, a coupler 40 mounted at the end of the column for movement of limited extent relative thereto, wedge means in frictional engagement with said column, means whereby said coupler moves said wedge means relative to said column throughout said 45 limited extent and moves both said wedge means and column when said coupler moves beyond said limited extent, friction shoes held against longitudinal movement and disposed between the bolster and coupler in engagement with said 50 wedge means, and resilient means disposed at least in part between said bolster and coupler, said resilient means being operatively interposed between said friction shoes and column for resisting movement of said column and for maintaining frictional engagement between said shoes 55 and wedge means.

3. In a railway car, the combination of a body bolster, a column movable longitudinally relative thereto under draft and buffing shocks, a coupler 60 mounted at the end of said column for movement of limited extent relative thereto, wedge means extending inwardly from said coupler and movable therewith relative to said column throughout said limited extent, means for moving both said wedge means and column by said coupler when the latter moves beyond said limited extent, friction shoes held against substantial longitudinal movement and disposed between said bolster and coupler in engagement with said 65 wedge means, and resilient means disposed in part between said shoes and bolster and extending through an opening in said bolster, said resilient means being operatively interposed between said friction shoes and column for resisting movement of said column and for maintaining frictional engagement between said shoes and wedge means.

4. In a railway car, the combination of a body bolster, a column movable longitudinally relative thereto under draft and buffing shocks, a coupler 5 mounted at the end of said column for movement of limited extent relative thereto, wedge means extending inwardly from said coupler and connected therewith for movement relative to said column throughout said limited extent, means for moving both said wedge means and column by said coupler when the latter moves beyond said limited extent, friction shoes held against substantial longitudinal movement and disposed between the bolster and coupler in engagement 10 with said wedge means, resilient means disposed inwardly of said shoes and extending through an opening in said bolster, means operatively connecting said coupler with one end of said resilient means for compressing the same on movement of said coupler, and means operatively connecting the other end of said resilient means with said shoes whereby compression maintains said shoes in engagement with said wedge means.

5. In a railway car, the combination of a column movable longitudinally relative to the car body under draft and buffing shocks, a coupler mounted at the end of said column for movement of limited extent relative thereto, wedge means frictionally engaging said column and movable relative thereto by said coupler throughout said limited extent, means for moving both said wedge means and column by said coupler when the latter moves beyond said limited extent, friction shoes engaging said wedge means, means holding said shoes against substantial longitudinal movement, resilient means operatively connected to said friction shoes for maintaining frictional engagement of said shoes with said wedges and of said wedges with said column, and means operatively connecting said coupler and resilient means whereby the latter is compressed during said movement of limited extent relative to said column and also during said movement of both said wedge means and column.

6. In a railway car, the combination of a body bolster, a column movable longitudinally relative thereto under draft and buffing shocks, a coupler mounted at the end of said column for movement of limited extent relative thereto, wedge means frictionally engaging said column and movable relative thereto by said coupler throughout said limited extent, means for moving both said wedge means and column by said coupler when the latter moves beyond said limited extent, friction shoes disposed between said coupler and bolster in engagement with said wedge means, means holding said shoes against substantial longitudinal movement, resilient means disposed inwardly of said shoes and extending through an opening in said bolster, and means operatively interposing said resilient means between said coupler and said shoes whereby said resilient means is compressed on movement of said coupler to maintain frictional engagement of said shoes with said wedge means and of said wedge means with said column.

7. In a railway car, the combination of a body bolster, a column movable longitudinally relative thereto under draft and buffing shocks, a coupler mounted at the end of said column for movement of limited extent relative thereto, wedge means frictionally engaging said column and movable relative thereto by said coupler throughout said limited extent, means for moving both

- 5 said wedge means and column by said coupler when the latter moves beyond said limited extent, friction shoes engaging said wedge means, means for holding said shoes against substantial longitudinal and lateral movement and comprising stationary friction surfaces engaging said shoes, and resilient means operatively engaging said shoes, and means operatively connecting said resilient means and coupler.
- 10 8. In a railway car, the combination of a body bolster, a column movable longitudinally relative thereto under draft and buffing shocks, a coupler mounted at the end of said column for movement of limited extent relative thereto, wedge means frictionally engaging said column and movable relative thereto by said coupler throughout said limited extent, means for moving both said wedge means and column by said coupler when the latter moves beyond said limited extent, friction shoes engaging said wedge means, means connected to said bolster for holding said shoes against substantial longitudinal and lateral movement and comprising stationary friction surfaces engaging said shoes and resilient means operatively engaging said shoes, and means operatively connecting said resilient means and coupler.
- 15 9. In a railway car, the combination of a body bolster, a column movable longitudinally relative thereto under draft and buffing shocks, a coupler mounted at the end of said column for movement of limited extent relative thereto, wedge means frictionally engaging said column and movable relative thereto by said coupler throughout said limited extent, means for moving both said wedge means and column by said coupler when the latter moves beyond said limited extent, friction shoes engaging said wedge means, means connected to said bolster for holding said shoes against substantial longitudinal and lateral movement and comprising stationary friction surfaces engaging said shoes and resilient means having one end operatively connected to said shoes, and means operatively connecting the other end of said resilient means with said wedge means.
- 20 10. In a railway car, the combination of a body bolster, a column movable longitudinally relative thereto under draft and buffing shocks, a coupler mounted at the end of said column for movement of limited extent relative thereto, wedge means frictionally engaging said column and movable relative thereto by said coupler throughout said limited extent, means for moving both said wedge means and column by said coupler when the latter moves beyond said limited extent, friction shoes engaging said wedge means, means connected to said bolster for holding said shoes against substantial longitudinal and lateral movement and comprising stationary friction surfaces engaging said shoes and resilient means disposed inwardly of said shoes and extending through an opening in said bolster, means operatively connecting one end of said resilient means with said shoes, and means operatively connecting the other end with said coupler.
- 25 11. In a railway car, the combination of a body bolster, a column movable longitudinally relative thereto under draft and buffing shocks, a coupler mounted at the end of said column for movement of limited extent relative thereto, wedge means frictionally engaging said column and movable relative thereto by said coupler throughout said limited extent, means for moving both said wedge means and column by said coupler when the latter moves beyond said limited extent, horizontally extending arms on said bolster connected at their ends by vertical walls, friction shoes held against substantial longitudinal movement and mounted for engagement with said vertical walls and having friction surfaces engaging said wedge means, and resilient means housed between said arms and operatively interposed between said friction shoes and column for resisting movement of said column and for maintaining frictional engagement of said shoes with said wedge means.
- 30 12. In a railway car, the combination of a body bolster, a column comprising spaced vertical walls and movable longitudinally relative to said bolster, a coupler mounted at the end of said column for movement of limited extent relative thereto, wedge means comprising spaced vertical surfaces one engaging each of said walls and movable by said coupler relative thereto throughout said limited extent, said members having inner wedge surfaces, means for moving both said wedge means and said column when said coupler moves beyond said limited extent, friction shoes between said members and in engagement with said wedge surfaces, means for holding said shoes against substantial longitudinal movement, and resilient means operatively interposed between said friction shoes and column for resisting movement of said column and for maintaining frictional engagement of said shoes with said wedge surfaces.
- 35 13. In a railway car, the combination of a body bolster, a column comprising spaced vertical walls and movable longitudinally relative to said bolster, a coupler mounted at the end of said column for movement of limited extent relative thereto, wedge means comprising spaced vertical surfaces one engaging each of said walls and movable by said coupler relative thereto throughout said limited extent, said members having inner wedge surfaces, means for moving both said wedge means and said column when said coupler moves beyond said limited extent, stationary friction means between said members and having surfaces inclined to said wedge surfaces, friction shoes each having surfaces engaging said friction means and wedge surfaces, and resilient means operatively interposed between said friction shoes and column for resisting movement of said column and for maintaining frictional engagement of said shoes with said friction and wedge means.
- 40 14. In a railway car, the combination of a body bolster, a column comprising spaced vertical walls and movable longitudinally relative thereto, a coupler mounted on said column for movement of limited extent relative thereto, a substantially U-shaped wedge means comprising spaced legs each having a vertical surface engaging one of said walls, the bight of the U operatively engaging said coupler for movement thereby relative to said column throughout said limited extent, said legs having inner wedge surfaces, friction shoes between said wedge surfaces, means holding said shoes against substantial longitudinal movement, resilient means operatively interposed between said shoes and column, and means for moving both said column and wedge means when said coupler moves beyond said limited extent.
- 45 15. In a railway car, the combination of a body bolster, a column comprising spaced vertical walls and movable longitudinally relative thereto, a coupler mounted on said column for movement of limited extent relative thereto, a substantially

U-shaped wedge means comprising spaced legs each having a vertical surface engaging one of said walls, the bight of the U operatively engaging said coupler for movement thereby relative to 5 said column throughout said limited extent, said legs having inner wedge surfaces, friction shoes between said wedge surfaces, means holding said shoes against substantial longitudinal movement, resilient means, a follower for one end of said 10 resilient means and engaged by said legs, means operatively connecting the other end of said wedge means with said friction shoes, and means operatively connecting said wedge means and column for movement together after said wedge 15 means moves through said limited extent.

16. In a railway car, the combination of a body bolster, a column comprising spaced vertical walls and movable longitudinally relative to said bolster, a coupler mounted at the end of said column 20 for movement of limited extent relative thereto, wedge means comprising spaced vertical surfaces one engaging each of said walls and movable by said coupler relative thereto throughout said limited extent, said members having inner wedge 25 surfaces, means for moving both said wedge means and said column when said coupler moves beyond said limited extent, horizontally extending arms extending from said bolster and connected at their ends by vertical walls, friction 30 shoes held against substantial longitudinal movement and mounted for engagement with said walls and having friction surfaces engaging said wedge means, resilient means housed between said arms and operatively engaging said shoes, 35 and means operatively connecting said resilient means and coupler.

17. In a railway car, the combination of a body bolster, a column comprising spaced vertical walls and movable longitudinally relative to said bolster, a coupler mounted at the end of said column 40 for movement of limited extent relative thereto, wedge means comprising spaced vertical surfaces one engaging each of said walls and movable by said coupler relative thereto throughout said limited extent, said members having inner wedge 45 surfaces, means for moving both said wedge means and column when said coupler moves beyond said limited extent, horizontally extending arms on said bolster connected by vertical walls 50 forming a stationary friction means, friction shoes on the inner and outer sides of said friction means in frictional engagement with the same and with said wedge surfaces, resilient means housed between said arms and operatively 55 connected with said shoes for urging the inner or outer shoes as the column moves in one or the other direction, and means operatively connecting said resilient means and coupler.

18. In a railway car of the type having a body 60 bolster and a draft and buffing column movable longitudinally relative thereto, combined bolster and cushion gear means comprising bolster construction and spaced walls extending longitudinally therefrom and connected adjacent their 65 ends by transverse walls, and cushion gear means housed by said walls and comprising resilient means and operative connections to said walls for maintaining said resilient means under compression.

70 19. In a railway car of the type having a body

bolster and a draft and buffing column movable longitudinally relative thereto, combined bolster and cushion gear means comprising bolster construction having an opening therethrough, spaced walls extending longitudinally from said bolster 5 construction at the sides of said opening, transverse walls connecting said longitudinal walls adjacent their ends, and cushioning means housed in said opening and by said walls, said cushioning means comprising a spring and operative connections to said walls for maintaining said spring under compression. 10

20. In a railway car of the type having a body bolster and a draft and buffing column movable longitudinally relative thereto, combined bolster 15 and cushion gear means comprising bolster construction and spaced walls extending longitudinally therefrom and connected adjacent their ends by transverse walls, cushioning means housed by said walls and comprising friction 20 shoes and a spring maintaining the same in engagement with said transverse walls, and operative connections from said spring to said walls whereby said spring is maintained under compression. 25

21. In a railway car of the type having a body bolster and a draft and buffing column movable longitudinally relative thereto, combined bolster and cushion gear means comprising bolster construction and spaced walls extending longitudinally therefrom and connected adjacent their 30 ends by transverse walls, cushioning means housed by said walls and comprising friction shoes engaging said transverse walls on the inner and outer sides thereof, a spring disposed between said longitudinal walls and engaging said inner shoes at one end, and means operatively connecting the other end to said outer shoes whereby said spring is interposed under compression between the inner and outer shoes. 35 40

22. In a railway car of the type having a body bolster and a draft and buffing column movable longitudinally relative thereto, combined bolster and cushion gear means comprising bolster construction having an opening therethrough, walls 45 extending longitudinally from said bolster at the sides of said opening, transverse walls connecting said longitudinal walls adjacent their ends, and cushion gear means housed in said opening and walls and comprising friction shoes engaging 50 said transverse walls and a spring extending into said opening and operatively connected at one end to said walls, said spring being compressed and its other end bearing against said shoes.

23. In a railway car of the type having a body 55 bolster and a draft and buffing column movable longitudinally relative thereto, combined bolster and cushion gear means comprising bolster construction having an opening therethrough, walls 60 extending longitudinally from said bolster at the sides of said opening, transverse walls connecting said longitudinal walls adjacent their ends, and cushion gear means housed in said opening and walls and comprising friction shoes engaging the inner and outer sides of said transverse walls, 65 a spring extending into said opening and engaging said inner shoes at one end, and means operatively connecting the other end to said outer shoes.
